US0D1111868S

(12) **United States Design Patent** (10) Patent No.: **US D1,111,868 S**
(45) Date of Patent: ** Feb. 10, 2026

(54) **LASER RADAR**

(71) Applicant: **HangZhou YuShu TECHNOLOGY CO., LTD.**, Hangzhou (CN)

(72) Inventors: **Xingxing Wang**, Hangzhou (CN);
Xiaoyan Bai, Hangzhou (CN)

(73) Assignee: **HANGZHOU YUSHU TECHNOLOGY CO., LTD.**,
Hangzhou (CN)

(**) Term: **15 Years**

(21) Appl. No.: **29/878,334**

(22) Filed: **Jun. 20, 2023**

(30) **Foreign Application Priority Data**

Dec. 20, 2022 (CN) 202230849892.8

(57) **CLAIM**

The ornamental design for a laser radar as shown and described.

DESCRIPTION

FIG. 1 is a top perspective view of a laser radar showing our new design;

FIG. 2 is a bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines depict portions of the laser radar that form no part of the claimed design.

1 Claim, 8 Drawing Sheets
